UNITED STATES PATENT OFFICE.

RICHARD H. WELLES, OF KENOSHA, WISCONSIN.

DESIGN FOR A HEADLIGHT.

40,844.

Specification for Design.

Patented Aug. 30, 1910.

Application filed April 21, 1910. Serial No. 556,909. Term of patent 7 years.

To all whom it may concern:

Be it known that I, RICHARD H. WELLES, a citizen of the United States, residing in the city of Kenosha, county of Kenosha, and State of Wisconsin, have invented a new, original, and ornamental Design for Headlights, of which the following is a specification, reference being had to the accompanying drawings, forming a part thereof.

In the drawings—Figure 1 is a perspective view of my new design; Fig. 2 is a side elevation of the same; Fig. 3 is a top plan view.

The salient or distinguished features of the design may be briefly described as follows: An exteriorly octagonal body portion 1, terminates at its forward end in an outwardly flaring portion 2, likewise octagonal in exterior contour. This flaring portion is provided with ring rim 3 which serves as a

seat for the door structure 4. The latter is of a diameter extending the main body of the headlight. The rear inclosure of the main body 1 presents an exteriorly convex surface 5 terminating in a reduced similarly formed extension 6. Surmounting the main body of the headlight is a low rectangular ventilator or dome 7, the forward ends of which merge into the curve of the flaring portion 2 as shown at 8. The side of the main body is provided with supporting brackets 9 of novel configuration.

I claim:

The ornamental design for a headlight as shown and described.

RICHARD H. WELLES.
